UNITED STATES PATENT OFFICE.

GEORGE H. DODGE, OF WAVERLEY, MASSACHUSETTS.

PAPER BOX.

1,323,170.

Specification of Letters Patent. Patented Nov. 25, 1919.

Application filed April 10, 1918. Serial No. 227,667.

To all whom it may concern:

Be it known that I, GEORGE H. DODGE, a citizen of the United States, residing at Waverley, county of Middlesex, State of 5 Massachusetts, have invented an Improvement in Paper Boxes, of which the following description, in connection with the accompanying drawing, is a specification, like characters on the drawing representing like 10 parts.

This invention relates to paper boxes of that type which are made by folding into box shape a one-piece integral blank, and the objects of the invention are to provide a 15 novel box of this type which will securely hold any contents which may be placed therein, and also to provide a novel blank from which the box is made.

In order to give an understanding of my 20 invention, I have illustrated in the drawings a selected embodiment thereof, which will now be described, after which the novel features will be pointed out in the appended claims.

25 In the drawings, Figure 1 is a view of the blank from which the box is made;

Fig. 2 is a perspective view showing the box partially folded;

Fig. 3 is a section on the line 3—3 Fig. 2.

30 The blank from which the box is made is cut into the shape shown in Fig. 1, and it comprises the section 1 that constitutes the bottom of the box, the section 2 that constitutes the top of the box, and the

35 section 3 which constitutes one end of the box and which connects the sections 1 and 2 along the lines 4 and 5. The bottom section 1 is provided at one end with the end flap 6 which is foldable at right angles to

40 the bottom 1 along the line 7 and is also provided with the two side flaps 8 on opposite sides which are foldable at right angles to the bottom along the lines 9.

The blank is provided with the two slits 45 10 at the junction of the sides 8 and the bottom 1 and is also provided with a slit 11 at the junction of the end flap 6 with the bottom 1.

The top 2 of the box is provided on each 50 side with the side flaps 12 which are connected to the top and are foldable at right angles thereto along the lines 13, and said top is also provided with the end flap 14 which is connected and foldable at right 55 angles thereto along the line 15. Each

side flap 12 has formed integral therewith a laterally-extending tab 16 and the end flap 14 has integral therewith a laterally-extending tab 17.

In order to form the complete box from 60 the above-described blank, the side flaps 8 and the end flap 6 are folded upwardly into position at right angles to the bottom, as shown in Fig. 2, and the end 3 is also folded up at right angles, thus making a box body. 65 The box body thus formed may then be filled, after which the top 2 is folded down on top of the upturned side and end flaps 8 and 6, and the side flaps 12 of the top and the end flap 14 of the top are folded 70 down at right angles thereto so as to overlie the side and end flaps 8 and 6 associated with the bottom. As the side flaps 12 are folded against the outside of the side flaps 8, the tabs 16 are inserted through the slits 75 10, said tabs extending parallel to the bottom. Since the apertures 10 are at the junction line between the side flaps 8 and the bottom 1, said tabs will lie directly on the bottom. During the folding of the end 80 flap 14 of the top the tab 17 thereof is inserted through the slit 11, thus locking said end flap in place. The three tabs all of which lie close against the bottom operate to securely hold the end flap 14 and side 85 flaps 12 of the top in proper position, thus holding the box closed.

A box of this construction is well adapted for holding candy or a similar article. It can be inexpensively made and is so constructed that it will hold its box shape after the tabs have been inserted through the slits. 90

I claim:

1. A box made from a one-piece blank and comprising a bottom having integral 95 therewith upturned side flaps at two opposite sides and an end flap at one end and having tab-receiving slots formed at the junction of the bottom and the side and end flaps extending therefrom, and a top 100 integrally connected at one end to the other end of the bottom by a section which constitutes one end of the box, said top having side flaps integral therewith on two opposite sides and an end flap integral therewith 105 at the end, the side and end flaps of the top overlying and being co-extensive in area with the upturned side and end flaps of the bottom, and tabs integral with the side and end flaps of the top extending directly from 110

the edges thereof and at right angles thereto, said tabs passing through the slots and overlying the bottom.

2. A blank for a box comprising a bottom 5 section having two side flaps integral therewith at opposite sides and an end flap extending from one end thereof, a top section integrally connected at one end to the other end of the bottom by a connecting section 10 and having an end flap extending from the opposite end which is of the same size and shape as the end flap extending from the bottom, said top section also having two

side flaps extending from opposite sides which are of the same shape and size as the 15 side flaps extending from the bottom section, each side flap and the end flap of the top section having integral therewith a laterally-extending tab situated centrally thereof, said blank having tab-receiving slots formed 20 at the junction between the bottom and side and end flaps extending therefrom.

In testimony whereof I have signed my name to this specification.

GEORGE H. DODGE.
